CLAIM

The ornamental design for a boot, as shown and described.

DESCRIPTION

FIG. 1 is a front perspective view of the boot showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of an alternative embodiment of the design shown in FIGS. 1-7;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines depicting portions of the boot sole show portions of the boot that form no part of the claimed design.

1 Claim, 14 Drawing Sheets
